UNITED STATES PATENT OFFICE.

FOSTER MILLIKEN, OF NEW YORK, N. Y.

DESIGN FOR A METALLIC POST.

SPECIFICATION forming part of Design No. 21,074, dated September 29, 1891.

Application filed April 25, 1891. Serial No. 390,512. Term of patent 14 years.

To all whom it may concern:

Be it known that I, FOSTER MILLIKEN, a citizen of the United States, residing at New York city, in the county and State of New York, 5 have invented and produced a new and original Design for Metallic Posts, of which the following is a specification, reference being had to the accompanying drawing, forming part thereof, which represents an isometric 10 perspective of a post embodying my design.

The design of the post in plan view consists of two oppositely-opposed truncated-cone figures A and B, the base whereof is carried at an angle outward from the sides, in conse-

quence of which formation figures b appear 15 as a portion of the cone figures, and the flange figures are connected by cylindric figures a and a'. The cone figures are also decorated by flange figures d, which are oppositely disposed to the similar figures b. 20

I claim—

The design for a metallic post, substantially as herein shown and described.

FOSTER MILLIKEN.
